VIBRATING LOUNGE

Richard Thomas, 14 9th Place, Long Beach, Calif.

Filed June 27, 1961, Ser. No. 65,738

Term of patent 3½ years

(Cl. D83—1)

FIG. 1.

FIG. 2.

FIG. 3.

FIG. 4.

FIG. 5.

FIG. 1 is a front elevational view of a vibrating lounge, showing my new design;

FIG. 2 is a top plan view thereof;

FIG. 3 is a rear elevational view thereof, taken from the back of FIG. 1;

FIG. 4 is an end elevational view thereof, taken from the right of FIG. 1; and

FIG. 5 is an end elevational view taken from the left of FIG. 1, as seen in a lowered position.

I claim:

The ornamental design for a vibrating lounge, as shown.
